US00D404354S

United States Patent [19]

Witek et al.

[11] Patent Number: Des. 404,354

[45] Date of Patent: **Jan. 19, 1999

[54] **WINDSHIELD WIPER BLADE CONNECTOR**

[75] Inventors: **James Patrick Witek**, Michigan City; **Richard Allen Herring**, Granger; **Alan Jeffrey Stahlhut**, Valparaiso; **William Arthur Powell**, Winamac, all of Ind.

[73] Assignee: **Cooper Industries, Inc.**, Houston, Tex.

[**] Term: **14 Years**

[21] Appl. No.: **62,757**

[22] Filed: **Nov. 22, 1996**

Related U.S. Application Data

[63] Continuation-in-part of Ser. No. 746,270, Nov. 8, 1996.

CLAIM

The ornamental design for a windshield wiper blade connector, as shown and described.

DESCRIPTION

FIG. 1 is a perspective view of a windshield wiper blade connector showing a first embodiment of our new design; FIG. 2 is a side elevation view thereof;

FIG. 3 is a side elevation view thereof, opposite that shown in FIG. 2;

FIG. 4 is a front elevation view thereof;

FIG. 5 is a rear elevation view thereof;

FIG. 6 is a top plan view thereof;

FIG. 7 is a bottom plan view thereof;

FIG. 8 is a perspective view of a windshield wiper blade connector showing a second embodiment of our new design;

FIG. 9 is a side elevation view thereof;

FIG. 10 is a side elevation view thereof, opposite that shown in FIG. 9;

FIG. 11 is a front elevation view thereof;

FIG. 12 is a rear elevation view thereof;

FIG. 13 is a top plan view thereof; and,

FIG. 14 is a bottom plan view thereof.
